CHILD'S TRICYCLE

Walter Lines, Merton, London, England, assignor to Lines
Bros. Limited, London, England, a British company

Application April 28, 1955, Serial No. 35,718

Term of patent 14 years

(Cl. D34—15)

Fig. 3.

Fig. 4.

Fig. 1 is a perspective view of a tricycle, showing my new design;

Fig. 2 is a perspective view thereof showing the opposite side;

Fig. 3 is a rear elevational view thereof; and

Fig. 4 is a bottom plan view thereof.

I claim:

The ornamental design for a child's tricycle, substantially as shown.
